UNITED STATES PATENT OFFICE.

HENRY P. KIRKHAM, OF BROOKLYN, NEW YORK.

COFFER-DAM.

SPECIFICATION forming part of Letters Patent No. 404,718, dated June 4, 1889.

Application filed May 15, 1888. Serial No. 273,969. (No model.)

To all whom it may concern:

- Be it known that I, HENRY P. KIRKHAM, of Brooklyn, county of Kings, and State of New York, have invented a certain new and useful 5 Improvement in Cofferdams, of which I declare the following to be a full, clear, and exact description, reference being had to the accompanying drawings, forming part of this specification.
- 10 This invention relates to improvements in coffer-dams; and the invention consists of a coffer-dam constructed in the manner herein shown, described, and claimed.
- In the accompanying sheet of drawings, 15 Figure 1 is a plan or top view of the coffer-dam; Fig. 2, a cross-section of same; Fig. 3, an end view showing gates; Fig. 4, elevation of sliding gate.
- Similar letters of reference indicate like 20 parts in the several figures.
- This invention is mainly an improvement on the coffer-dam heretofore patented by me on the 31st of January, 1882, in Patent No. 253,067. In that patent the hinged gates are 25 shown only on the upper section of the dam, the lower section being closed by bulk-heads. This construction answered the purpose for an ordinary steamer provided with but one screw placed in line with the keel of the 30 ship; but since the introduction of this dam vessels with the so-called "twin screws" are being employed, and these screws project from the quarters of the vessel on each side of the stern-post, and such a dam could not 35 be used with facility for the last-named ships, because the twin screws would meet obstruction in the bulk-heads or closed part of the front of the dam below the hinged gates. Therefore, to adapt the dam to vessels pro- 40 vided with twin screws, I hinge the doors A to the sides of the dam as far as the ballast-tanks B will permit, and then slope off the

lower part of the hinged doors to correspond to the shape of the tanks. The advantage of this form of hinged door is that when the coffer-dam is used in shallow water—in which case it may rest upon the bottom of the harbor before the doors A are closed preparatory to pumping out and floating the dam in place under the ship—there can be no danger that 45 the closing of the doors and the subsequent operation of the dam would be seriously interfered with by the mud, &c., that might be scraped up by doors of another form in the process of closing them. This difficulty could 50 not occur with the dam as shown in the patent above mentioned, because of the closed bulk-heads B, above which the doors were hinged; but such construction would not admit a ship with twin screws, and to adapt the 55 dam to vessels having such screws and to prevent the doors in shallow water from scraping up the bottom, I hinge the doors to the edges a of the dam, so that I can have the largest possible opening and let their bottoms extend to and follow the form of the ballast-tanks B, which practically form the sills of 60 the doors.

The other features of the construction of my dam improved as described, not differing 65 materially from such features patented by me as aforesaid, I need not again describe.

Having now described my invention, what I claim as new, and desire to secure by Letters Patent, is—

In a coffer-dam, the gates A, hinged to the sides of the dam and extending from the top to the bottom of the dam, said gates having oblique bottom edges, as and for the purpose described.

HENRY P. KIRKHAM.

In presence of—
D. A. CARPENTER,
G. M. FIELD.
